[57] CLAIM

The ornamental design for a sunning board for a bass boat, as shown and described.

DESCRIPTION

FIG. 1 is a side perspective view of a sunning board for a bass boat showing my new design, the broken lines are for illustrative purposes only and form no part of the claimed design;

FIG. 2 is a top plan view thereof;

FIG. 3 is a left side elevational view thereof, it being understood that the pedestal of the board has been omitted for clarity of illustration;

FIG. 4 is a left end elevational view of FIG. 3;

FIG. 5 is a right end elevational view of FIG. 3;

FIG. 6 is a right side elevational view of FIG. 3;

FIG. 7 is a bottom plan view of FIG. 3.
